AQUARIUM FILTER BASE

Roth K. Christopherson, 5404 Plaza,
Wichita, Kans. 67208

Filed Nov. 4, 1974, Ser. No. 520,744

Term of patent 14 years

Int. Cl. D23—01

U.S. Cl. D23—4

FIG. 1 is a top perspective view of an aquarium filter base showing my new design;

FIG. 2 is a side elevational view;

FIG. 3 is a left end elevational view; and

FIG. 4 is a cross sectional view taken along line 4—4 of FIG. 1.

I claim:

The ornamental design for an aquarium filter base, as shown.
